Primary Examiner—Stella M Reid*Assistant Examiner*—Mark A Goodwin*(74) Attorney, Agent, or Firm*—David A. Burge(57) **CLAIM**

We claim the ornamental design for front portion of the housing of a handle and housing assembly, as shown and described.

DESCRIPTION

FIG. 1 is a top front left perspective view of a front portion of the housing of a handle and housing assembly showing our new design;

FIG. 2 is a front view thereof;

FIG. 3 is a left side view, the right side being a mirror image thereof;

FIG. 4 is an end view thereof; and,

FIG. 5 is an opposite end view thereof.

The broken line disclosure in several of the views of other features is provided for illustrative purposes only and forms no part of the claimed design.
